United States Patent Office

Des. 176,265
Patented Dec. 6, 1955

176,265

FINGER RING OR THE LIKE

Adolph Katz, Providence, R. I., assignor to Coro, Inc.,
New York, N. Y., a corporation of New York

Application February 25, 1955, Serial No. 34,710

Term of patent 7 years

(Cl. D45—10)

Fig. 1

Fig. 2

Fig. 3

Fig. 1 is a plan view of a finger ring or the like, showing my new design.

Fig. 2 is an edge view thereof.

Fig. 3 is a side elevational view of the finger ring as shown in Fig. 1.

I claim:

The ornamental design for a finger ring or the like, substantially as shown.
